UNITED STATES PATENT OFFICE.

JAMES F. FERGUSON AND CHARLES C. POST, OF BURLINGTON, VERMONT.

SUGAR-EVAPORATOR.

SPECIFICATION forming part of Letters Patent No. 308,407, dated November 25, 1884.

Application filed August 31, 1883. (No model.)

To all whom it may concern:

Be it known that we, JAMES F. FERGUSON and CHARLES C. POST, citizens of the United States, residing at the city of Burlington, in the county of Chittenden and State of Vermont, have invented certain new and useful Improvements in Sugar-Evaporators, of which the following is a specification, reference being had therein to the accompanying drawings.

Our invention relates to improvements in evaporators designed to reduce sap or other saccharine liquids to sirup or sugar; and the object of our improvements is to so arrange the construction of our apparatus that the sap or other saccharine liquid shall be so treated in the process of evaporation as to produce in the shortest time the largest and purest quality of sirup, and hence the greatest quantity of the best sugar, inasmuch as every portion of our pan is at all times under the entire control of the operator, so that the sap or saccharine liquid can be readily subjected to whatever degree of heat is deemed advisable, and the causes which prevent the best results are either avoided or so managed as to have little or no injurious effect.

Our invention consists in the combination, with a fire-chamber of comparatively small dimensions, and connected by suitable horizontal flues to a chimney or smoke-flue, of a fixed pan which extends over the entire fire-chamber and also the horizontal flues communicating with the smoke-flue. That portion of the pan which is immediately over the fire is divided into suitable transverse sections provided with suitable gate-openings between them and suitable slides and cold-air flues beneath them, whereby the flow of the sirup may be controlled at any desired point, and the degree of heat to which each section shall be subjected such as shall best conduce to the desired result. The remainder of the pan is divided into longitudinal sections having suitable hot-air flues so arranged and connected together that a regular and continuous volume of sap or saccharine liquid enters the pan at the point of greatest heat, and thence passes into the first section, where the scum or fecal matter can be conveniently removed, and thence steadily flows through the several longitudinal sections, where, by the arrangement

of the hot-air flues, it is subject to a rapid and continuous evaporation until, as it enters the transverse sections, it is either ready to be siruped off, or, by being still further subjected to a gradually-decreasing heat, regulated by dampers, it reaches the point where crystallization successfully takes place. By this construction the usual expense of building and 55 permanently maintaining an extensive arch is greatly reduced, the entire heat utilized, and the amount of fuel required proportionately diminished. By means of a convenient arrangement of dampers and upper and lower 60 series of hot-air flues beneath the longitudinal sections heat may be applied in such degree as may be desired; or, as the process of evaporation draws to a close the heat may be entirely cut off from, first, the sectional flues; 65 second, from the bottom of the pan; and, lastly, diverted to the chimney in another way, all of which will be more fully described hereinafter. I attain these objects by the apparatus illustrated in the accompanying drawings, 70 75 in which—

Figure 1 is a perspective view of the evaporator-pan. Fig. 2 is a perspective view of the bottom of the same pan, looking toward its rear end. Fig. 3 is a perspective view of 80 the same pan, looking toward the front end and showing the heating-flues, sections, and gates. Fig. 4 is a perspective view of the arch, flues, and chimney. Fig. 5 is a cross-section of the arch on the line x y. Fig. 6 is a perspective view of the gate and frame. Fig. 7 is a perspective view of the evaporator complete.

Similar letters refer to similar parts throughout the several views.

A represents the arch or fire-chamber, of 90 rectangular shape and suitable construction, preferably from three to four feet in length.

B is the door opening into the same, and C the fire-grating. Near the top of the interior 95 end of the arch A is a flue, F, of the same width as the arch. It extends horizontally any length desired, and connects with the chimney or smoke-flue G. The upper portions of the flue F at each end are open to 100 form, when desired, a direct draft from the fire-chamber to the chimney, directly below the bottom of the pan. By this arrangement heat can be more easily retained in the lower

portion of the flue, the openings being closed by the dampers H and I.

Below the flue F and leading from the fire-chamber to the chimney is a smoke pipe or pipes, J. Its opening into the former is regulated by the valve or damper j. The several valves or dampers are conveniently operated by handles at the side of the apparatus.

K is a rectangular evaporating-pan, made of metal, and of sufficient size to cover the entire fire-chamber A and the flue F by which it is supported. The connection between the pan K and its supports is made air-tight by means of a metallic rim or strip, L, so arranged as to form a ledge around the pan, the space intervening between it and the lower edge of the pan being filled in with suitable packing material, so as to effectually prevent any chilling of the pan by the ingress of cold air beneath it, as well as the escape of any heat or flame which might scorch or burn the sides of the pan or the wooden guard around its upper edge. The portion of the pan over the fire-chamber is divided transversely into two or more sections, M, according to the length of the arch, sufficient space being left over the rear end of the arch for the section N, which extends from one side of the pan to the outlet p of the longitudinal section O, through which the syrup is admitted into the first of the transverse sections M. From the section N the pan is divided longitudinally by partitions P into three or more sections, Q, according to the width of the pan and the requirements for evaporation. Within each longitudinal section and about one inch above its bottom are one or more hot-air tubes or flues, R, communicating with the fire-chamber through the heating-chamber r within the section N and the flue of the chimney, thus forming a direct connection of the furnace with the chimney for the passage of heat and smoke. If the sides of the pan are about ten inches in height, the tubes R are from three to five inches square. The opening between the bottom of the chamber r and the fire-chamber is closed by the slide or damper S. In the rear of the chimney opposite the ends of the tubes R is an opening closed by the door T, to allow a swab to be passed into the tubes to clean them, as occasion may require, without removing the pan. At alternate ends of the partitions P openings m are provided for the under and over flow of the sap as it flows through the sections, the former being at the bottom of the partition and the latter at a sufficient height above the tubes R to insure their being covered during the process of evaporation.

In order that the scum or fecal matter may be removed as far as possible in the early process of boiling the side section, Q, may be of greater width than the others, so that as the scum is naturally driven by the effect of the boiling to the cooler side of the section, which is the outside of the pan, it can be conveniently removed. To render this separation more effectual, a cloth strainer, U, with a met-

al tube or mouth-piece is removably attached to the overflow of this section, to retain whatever is thrown to the surface by ebullition, and escapes the skimming. As the boiling process proceeds and the sap flows into the siruping-off section M, a deposit known as "silica" is frequently formed. To separate this deposit, which is heavier than the sap, a pocket, Y, with its cock z, is attached to the bottom of one or more of the sections M, into which it opens for the purpose of collecting the deposit as it flows through the section. The degree of heat which is required for the siruping-off sections M is regulated by the slides or dampers v under each section. These are perforated or solid, as desired. Above these slides are openings w through the sides of the fire-chamber, which can be closed at will. They are designed to admit a current of cold air beneath each section should it be desired to still further reduce their temperature. The sections discharge their contents into each other through the gates d, located at the bottom of the partitions, which separate them at their alternate ends. As these gates require to be absolutely water-tight, so that the depth of the sap in any section may be varied at will, it is apparent that the slide ordinarily used for such purposes cannot be successfully employed.

The gate as constructed by us and shown in Fig. 6 consists of a metallic frame, b, which is attached to the partition of any section through which an opening is desired, and is so arranged as to closely fit the vertical slide d. To the lower and side edges of this slide, which is made of wood, is attached a packing made of felt or other fibrous material, to prevent the passage of any sap around the slide when closed. An opening, e, through the bottom of the frame b, and a corresponding opening, f, through the partition allows the sap to flow readily from one section to the other when the slide is raised. Each section can be emptied through cocks a.

In operation the entire pan is first covered with sap, and the cold sap is then supplied continuously to the pan at the section N, where, by reason of the central position of the section on the line of direct draft and the location within it of the heating-chamber r, it can be at once subjected to the most intense heat. Its flow is rendered regular and continuous by its passage through a suitable gage. Passing thence into the side section, Q, where it is skimmed, it flows from one section to another in alternate directions until it covers the entire pan, the depth in the sections M being governed by the gates d. The process of boiling is then commenced. The valve j is first closed and the dampers H and I opened till the tubes R are covered by the sap, when the slide S is opened and the damper I closed, which diverts the entire heat-current into the tubes R. The sap being thus subjected to the heat retained in the flue F, and that which passes from the cham-

bers *r* through the tubes *R*, is soon raised to a boiling-point, and the process of evaporation rapidly proceeds, the sweetness of the sap continually increasing as it flows from section to section. The great extent of heating-surface thus provided beneath and through the sap, greatly hastens the process of evaporation, and thus prevents injury to the sap by exposure to the air. By means of the water-tight gates *d* the liquid is run in whatever quantity desired into the siruping-off sections *M*, from whence it can be drawn according to the quality or weight desired, that drawn from the last section being ready for crystallization.

15 As the process of evaporation draws to an end close the slide *S*, which excludes the heat from the tubes *R*, and prevents their burning when not covered by the sap. The heat is then diverted into the flue *F* by opening the damper *I* for the purpose of boiling the sap to its lowest extent, after which the dampers *H* and *I* are closed and the damper *j* opened, thereby diverting the entire heat from the bottom of the pan over the flue *F* into the chimney 25 through the under flue, *J*. This avoids the necessity of removing the pan while the sirup is being siruped off or sugared off in the transverse sections *M*. By means of the slide-dampers *v* the heat can be shut off from each 30 sirup-off section *M* as soon as it is empty, thus avoiding injury from burning.

By the above-described construction the heat required to reduce the sap is gathered directly in a large reservoir beneath the pan, 35 where it is completely absorbed and utilized, thus avoiding the necessity for an extensive fire-chamber, thereby greatly economizing, both in the expense of construction and the amount of fuel required. The arrangement 40 of the heating-flues in each evaporating-section preserves all the advantages of deep-boiling, and prevents undue precipitation of "grit" or silica until the liquid has reached the density of heavy sirup or for sugaring off, and 45 then a pocket is provided for it. At the same time the entire work is performed without necessitating the inconvenient removal of pans.

We are aware that evaporator-pans subdivided into transverse and longitudinal sections communicating by openings closed by 50 dampers, the latter sections containing smoke-flues, have heretofore been used.

We are also aware that a pocket for catching and retaining impurities has been arranged on the outside of an evaporating-pan, and that heating-tubes have been arranged in the bottom of a pan.

We are further aware that means have been provided whereby the heat can be diverted from one side of the bottom of the pan to the other side or over the entire bottom at once. We do not, therefore, claim these features, broadly; but

We claim as novel and desire to secure by Letters Patent—

1. An evaporating apparatus consisting of the receiving-section *N*, having the heating-surface *r* therein, the longitudinal sections *Q* and *O*, communicating with section *N* and with each other, the heating-flues *R*, arranged in 70 said sections *Q* and *O*, and provided with the slide *s*, and the series of transverse communicating sections *M*, arranged directly over the fire and communicating with one of said longitudinal sections, combined with the large 75 heating flue or drum *F*, arranged under the said longitudinal sections, and having dampers *H* *I* for controlling the heat therein, and the heat and smoke diverting flue *J*, substantially as described.

2. The metallic rim or flange *L*, around the top of the furnace-wall, extending upwardly therefrom to receive and retain in position the evaporating-pan, and also a packing to render the joint between the two smoke, gas, and air 85 tight, substantially as described.

3. The pocket *Y*, arranged before the opening into and extending below the bottom of the sugaring-off pan, to separate and retain grit, dirt, and silica from the sirup, substantially as described.

4. In an evaporating-pan, a gate for regulating communication between adjacent sections, consisting of the frame *b* and slide *d*, provided with a liquid-tight packing, substantially as described.

In testimony whereof we do affix our signatures in presence of two witnesses.

JAMES F. FERGUSON.
